UNITED STATES PATENT OFFICE.

LAURENCE A. HAWKINS, OF SCHENECTADY, NEW YORK, ASSIGNOR, BY MESNE ASSIGNMENTS, TO UNION SWITCH AND SIGNAL COMPANY, A CORPORATION OF PENNSYLVANIA.

BLOCK-SIGNAL SYSTEM.

1,027,046.

Specification of Letters Patent. Patented May 21, 1912.

Application filed October 2, 1909. Serial No. 520,651

To all whom it may concern:

Be it known that I, LAURENCE A. HAWKINS, a citizen of the United States, residing at Schenectady, county of Schenectady, State of New York, have invented certain new and useful Improvements in Block-Signal Systems, of which the following is a specification.

My invention relates to block signal systems in which the signals for the blocks are arranged to give three indications, danger, caution and clear, and are controlled wholly through the track circuits. In a prior application, Serial No. 511,663, filed August 7, 1909, I disclosed a system of this character in which currents of different phases were supplied to the track circuit of each block and a pair of track relays were provided for each block, each relay having a track winding and a second co-operating winding supplied with current independently of the track circuit, one relay being responsive to current in the track circuit from the transformer for that track circuit regardless of variations in phase in that current, and the other relay being responsive to current of one phase only. This system, as compared with prior systems for accomplishing the same results, had the advantages, first, that the relays were all of the efficient two winding type; second, that since one of the relays of each pair was not affected by the change in phase of the track current the change could be made gradually so as to maintain that relay energized and hence it was unnecessary to use quick acting or snap switches for controlling the track circuit current, and third, that by properly arranging the connections of adjacent blocks all possibility of a false clear signal, due to breaking down of the insulated joints between blocks, was avoided.

My present invention consists in a modification of the system of my former application. In the present case, instead of employing different phases for the track currents, I employ different frequencies and so arrange the system that all the advantages of the system of my prior application are still obtained.

My invention will best be understood by reference to the accompanying drawings, in which—

Figure 1 shows diagrammatically a block

signal system arranged in accordance with my invention, and Fig. 2 shows a modification of the same.

In the drawings, A, A', A² and A³ represent the rails of four blocks.

B', B² and B³ represent signals at the entrance to blocks A', A² and A³, respectively. These signals are arranged to give three indications of danger, caution or clear, either as indicated by a three-position arm or by the equivalent arrangement of two two-position arms.

C' and C² represent alternating current generators of different frequencies. c, c' and c² represent transmission lines supplied with current from these generators, the conductor c being common to both frequencies.

D to D³ represent track relays, of which two are provided for each block. These relays are indicated diagrammatically as of the well-known induction type each comprising a short-circuited secondary member d actuating the relay contacts, a track winding d' and a co-operating winding or windings d² supplied with current independently of the track circuits. The relays D, D² and D³ are shown each with two windings d².

E to E³ represent transformers having their primaries connected to the transmission lines. The two transformers of each pair are connected to different frequencies.

F, F' and F² represent track transformers having their secondaries connected to, and supplying current to, the track circuits of the blocks A, A', A², respectively, and their primaries adapted to be connected to the secondaries of the transformers E to E³ through resistances g. The connections between the transformers F to F² and E to E³ are controlled by contacts b on the signal mechanisms. The connections between these contacts and the signals are shown diagrammatically in dotted lines.

With a train or car in block A³, as indicated at H, the track windings of relays D⁴ and D⁵ are short-circuited, so that the relay contacts are open and the signal B³ stands at danger or stop. In this position of signal B³ its contact b connects the primary of track transformer F² to the secondary of transformer E⁴ which has the frequency of generator C'. Relay D³ of block A² has its windings d² connected to the secondary

of transformer E^3 which has the frequency of generator C^2 , so that this relay D^3 is not affected by the current now supplied to block A^2 by transformer F^2 . Relay D^2 has 5 two windings d^2 , one of which is connected to the secondary of transformer E^2 which has the frequency of generator C' . The current in this winding d^2 co-operating with the current in the track winding d' produces a torque in relay D^2 which closes its contacts and causes signal B^2 to move from danger to caution position.

The operating mechanisms for the signals are not shown but it will be understood 15 that the conductor running directly from the contact of relay D^2 to the upper side of the signal blade controls the movement of the signal from stop to caution, while the other conductor extending from the contacts of 20 relay D^3 to the upper side of the blade controls the movement of the signal from caution to clear, the conductor extending from the lower side of the blade being common for both circuits. With signal B^2 in caution 25 position its contact b connects the primary of transformer F' to the secondary of transformer E^3 , so that the current in the track circuit of block A' has the frequency of generator C^2 . Since one of the 30 windings d^2 of relay D and the single winding d^2 of relay D' are supplied with current of this frequency both relays close their contacts, so that signal B' stands at clear.

When the car moves out of block A^2 into 35 the next block the condition of relays D^4 and D^5 is the same as that shown for relays D^2 and D^3 , so that signal B^3 will then move from stop to caution position, shifting the connecting of transformer F^2 40 from transformer E^4 to transformer E^5 . The contact b is so arranged, as indicated in the drawing, that the connection to transformer E^5 is made before the connection to transformer E^4 is broken so that relay D^2 45 is not deenergized during this change in the connections of the transformer F^2 and the switch contact b need not be made quick acting. While transformer F^2 is connected to transformer E^4 and E^5 a certain 50 amount of current flows through the secondaries of these two transformers in series, but it flows through both resistances g and is limited in amount by these resistances. The movement of signal B^2 from caution 55 to clear does not alter the connections of transformer F' , so that the signal B' is not affected. In each of the relays the greater portion of the current required for the relay torque may be supplied directly 60 to the windings d^2 so that the track current may be small. It will be noted that the track connections of each block are relatively reversed. Because of this reversal a breaking down of the insulated joints 65 between the blocks will produce a reverse

torque in the relays adjacent to the broken down joints so as to put the signals at danger.

Fig. 2 shows a modification of the system in which each of the relays has only one 70 winding d^2 in addition to the track winding. The windings d^2 of the relays of each pair are in this case supplied with currents of different frequencies. The track transformers F , F' and F^2 are permanently connected to the transformers E , E^2 and E^4 . When a signal stands at danger, as shown for signal B^3 , the relay D^3 of the preceding block is energized while relay D^2 is deenergized. When signal B^3 moves from stop to 80 caution it establishes a connection from the primary of transformer F' to the secondary of transformer E^3 also. Currents of both frequencies are, therefore, impressed on the primary of the track transformer, as is 85 shown for transformers F and F' , so that the current in the track circuit is the resultant of the two frequencies; consequently both relays D and D' are energized and the signal B' stands at clear. 90

Comparing the arrangement of Fig. 2 with that of Fig. 1, it will be seen that the circuit connections of Fig. 2 are somewhat simpler, but that this arrangement is somewhat less economical in respect to current 95 consumption, since, as long as the signals stand at clear or caution, the secondaries of each pair of transformers E and E' are connected in parallel through the resistances g so that a certain amount of current is 100 flowing through these transformer secondaries in series which produces no useful result. Other connections of relay windings and of transformers for obtaining in either 105 relays or transformers the resultant of both frequencies will be obvious to those skilled in the art. Furthermore, while I have shown my system in its simplest form, it will be understood that it can be extended and modified to cover various requirements 110 in signaling which arise in practice. Accordingly, I do not desire to limit myself to the particular connections and arrangement of parts shown and described but aim in the appended claims to cover all modifications which are within the scope of my 115 invention.

What I claim as new and desire to secure by Letters Patent of the United States, is,—

1. In a block signal system, track circuits 120 for the blocks, sources of current of different frequencies, supply connections for supplying currents from said sources to the track circuits, means controlled by train movements for varying said supply connections to 125 vary the frequencies of the currents supplied to the track circuits, and a pair of track relays per block having track windings and co-operating windings supplied with current independently of the track 130

circuits, one relay of each pair being responsive to current in the track circuit from the supply connections for that block regardless of the variations in said connections and the other relay being responsive to current with one arrangement only of said supply connections.

2. In a block signal system, track circuits for the blocks, signals for the blocks adapted to indicate danger, caution and clear, sources of current of different frequencies, supply connections for supplying current from said sources to the track circuits, means controlled by the movement of a signal from danger to caution for varying the supply connections of the preceding block to vary the frequency of the current delivered to the track circuit of said block, and a pair of track relays per block, controlling the signal indications, having track windings and coöperating windings supplied with current independently of the track circuits, one relay of each pair being responsive to current in the track circuit for that block regardless of the variations in the supply connections and the other relay being responsive to current with one arrangement only of said supply connections.

3. In a block signal system, track circuits for the blocks, means controlled by train movements for supplying to the track circuit of each block currents of either of two frequencies, and a pair of track relays per block having track windings and coöperating windings supplied with current independently of the track circuits, said coöperating windings being supplied with both frequencies in one relay of each pair

and with only one frequency in the other relay of the pair.

4. In a block signal system, track circuits for the blocks, signals for the blocks adapted to indicate danger, caution and clear, sources of current of two different frequencies, supply connections for supplying current from said sources to the track circuits of the blocks, means controlled by the movement of a signal from danger to caution for shifting the supply connections of the preceding block from one frequency to the other, and a pair of track relays per block, controlling the signal indications, having track windings and coöperating windings supplied with current independently of the track circuits, said coöperating windings being supplied with both frequencies in one relay of each pair and with only one frequency in the other relay of the pair.

5. In a block signal system, track circuits for the blocks, means controlled by train movements for supplying to the track circuit of each block currents of different frequencies, and a pair of track relays per block having track windings and coöperating windings supplied with current independently of the track circuits, one relay of each pair being responsive to each current supplied to the track circuit of the block and the other relay being responsive to one of said currents only.

In witness whereof, I have hereunto set my hand this first day of October, 1909.

LAURENCE A. HAWKINS.
